UNITED STATES PATENT OFFICE.

MURILLO DOWNER, OF CHICAGO, ILLINOIS.

BOILER WASHING AND REFILLING DEVICE.

Application filed March 19, 1927. Serial No. 176,684.

My invention relates to a device for blowing out, washing and refilling locomotive boilers and is for particular application for points, such as round houses, where locomotives are received and cared for. One object is the provision of means for reducing the smoking of locomotives in round houses. Another object is the provision of means for initially heating locomotive water and steam, or for initially supplying a locomotive with water and steam while minimizing the necessity of initial locomotive firing in order to raise steam. Another object is the provision of means for clearing and cleaning the locomotive boilers. Another object is the provision of means for employing the heated water and steam from the locomotives being cleaned for heating and supplying water and steam to outgoing locomotives.

Other objects will appear from time to time in the course of the specification and claims.

I illustrate my invention more or less diagrammatically in the accompanying drawings, wherein—

Figure 1 is a plan view; and

Figure 2 is an elevation.

Like parts are indicated by like symbols throughout the specification and drawings.

Whereas my invention is particularly adapted for use with round houses the structure of the round house itself is omitted since it forms of itself no part of the present invention and since a round house showing is unnecessary for the understanding of the present invention.

Referring to the drawings herein it will be understood that A indicates a blow-out pipe, that is to say a connection which is made, through whatever intermediate means may be necessary, with the locomotive boiler. It will be understood that when the locomotive is brought into the round house for servicing, a connection with the blow-out pipe A is made and the water and steam in the locomotive boiler is exhausted through such pipe into the separator A¹. Such separator is in the form of a cylinder A² and a bottom A³, the blow-out pipe being provided with a tangential connection A⁴ intermediate top and bottom of said cylinder. A⁵ is any suitable outlet valve through which sludge, dirt and other impurities may be exhausted, by the passage A⁶ to any suitable

sewer connection, such as the catch basin top A⁷. It will be understood that the valve A⁵ is thermostatically operated in response to the heat of the steam and water within the separator A¹. I do not claim the employment of any particular thermostatic valve but I illustrate a valve which is made responsive to the temperature of the steam or water by means of a pipe A⁸ extending from the tangential connection A⁴ to the cylinder A⁹ of the valve control means. The pipe A⁸ is shown as having the branches A¹⁰. The circuit is completed by the exhaust connection A¹¹ which branches as at A¹².

As the mixed water and steam passes from the blow-out pipe into the separator a separation is effected, the impurities settling to the bottom for disposal as above described. The steam passes through the passage B, from the top of the separator A¹, to the refill tank B¹. This steam tends to heat the water which, as below described, is supplied to the refill tank for refilling the boilers of outgoing locomotives. The purified water passes from the separator A¹ by the line B² to the washout tank B³ the purpose of which is to supply water for washing out locomotive boilers. The water so drawn passes from the washout tank B³ by the pipe line B⁴ and through the valve B⁵ to any suitable pump B⁶ herein diagrammatically shown as electrically operated by the motor B⁷. Such pump delivers water along the liquid line B⁸ which extends to the point of use, for example in a locomotive round house, and may be provided with any suitable number of branches, not herein shown. Since it is desirable to have the washout water at a temperature not too hot for use for example at 120° F., I provide a cold water line B⁹ in communication with the passage B⁴. This cold water serves to dilute the hot water of the washout tank, when necessary, in order to hold down the temperature of the water supplied for boiler washout purposes.

From the refill tank B¹ water is drawn through the liquid line C and pump C¹, actuated by the motor C² for delivery along the water line C³ through the air chamber C⁴ to the boiler C⁵. The boiler may be heated in any suitable manner but is herein shown as heated by any suitable oil burner. The details of the boiler do not per se form any part of the present invention but I illustrate the boiler as including besides the

cylindrical portion C⁵ a heater C⁶ provided with an oil burning device C⁷ having the two injector nozzles diagrammatically shown as C⁸. I illustrate diagrammatically automatic means for actuating the oil burner in response to fluctuations in temperatures. Thus I show a Y connection C⁹ at the top of the cylinder C⁵ one arm of which is provided with a safety valve C¹⁰ and the other with the line C¹¹ extending to the burner device C⁷. I do not illustrate the details of the pressure control since it forms no part per se of the present invention, but it will be realized that any suitable means may be employed for varying or cutting off the flame of the burners in response to pressure variations.

In addition to the pressure control I provide any suitable temperature control where- by the flame is turned up and down or on and off in response to variations in temperature. I do not describe or show the details of such temperature control, since they form no part of the present invention but I do illustrate the thermostatic element C¹⁵ in communication, through the pressure line C¹⁶, with the burner control mechanism C⁷.

In order to provide relief means for the boiler and cylinder C⁵ I provide a Y connection D the two arms of which extend to the refill tank B¹. In one arm is positioned the automatic pressure relief valve herein indicated as D¹, operative to permit the contents of the boiler C⁵ to blow off into the refill tank B¹ when a predetermined pressure is exceeded. D² indicates a thermostatically controlled heater valve adapted to permit the contents of the boiler C⁵ to flow into the refill tank B¹ when a predetermined temperature is reached. The refill tank thus not only supplies water to the boiler C⁵, but serves also to relieve the pressure therefrom, thus preventing any water waste. Furthermore the circulation of water or steam into the refill tank serves to maintain the temperature of the refill tank at or above the desired minimum. The refill tank B¹ is also supplied with a drain pipe D³ extending from the bottom of the refill tank to the catch basin top A⁷. D⁴ is any suitable control valve therefor.

The tank is also provided with an overflow line D⁵, extending from the upper part of the tank to the catch basin top A⁷.

Extending from the boiler C⁵ is the refill line E which may extend to a round house or other point of use and which serves to deliver to the boilers of the outgoing locomotives hot water and steam. The water and steam so delivered may for example be at a temperature of 340°, and under high pressure.

It will be realized that whereas I have described and shown a practical and operative device that nevertheless many changes

might be made in the size, shape, number and disposition of parts without departing from the spirit of my invention. I therefore wish my drawings and description to be taken as in a broad sense illustrative and diagrammatic rather than as limiting me to my specific showing herein made.

The use and operation of my invention are as follows:

In the application of my invention to round house practice the incoming locomotives are connected to the blow-out pipe A and mixed water and steam is blown from their boilers into the separator A¹. The steam passes thence by the passage B to the refill tank B¹. The water passes about the line B² to the washout tank B³. The refuse or sludge passes through the passage A⁶ to the catch basin. The escape of the sludge is controlled by a thermostatic valve which so operates that when hot water and steam are flowing into the separator, the valve is closed in response to the high temperature. When such water and steam have been exhausted from the separator the drop in temperature permits the control valve to open and to exhaust the sludge.

The water which escapes along the line B² is employed for washing out locomotive boilers or for other uses and is moved by the pump B⁶. It may be diluted with cold water flowing through the line B⁹.

The refill tank is the water source for the refilling of the outgoing locomotives. Water passes thence, driven by the pump C¹, to the boiler C⁵. The air cylinder C⁴ serves to provide the necessary air cushion. Hot water, under pressure, is exhausted from the boiler C⁵ along the refill line E to the round house for supply to the outgoing locomotives. Heating of the water in the boiler C⁵ is controlled both by pressure and by temperature as above described, the flame of the burner going on and off in response to increase or decrease, both of pressure and of temperature. Also water from the boiler C⁵ may circulate back into the refill tank B¹ through the line D and the automatic pressure relief valve D¹ and the thermostatically controlled relief valve D².

I claim:

1. In locomotive handling equipment, a blow-off and refill plant which includes an inlet connection adapted to be connected to a locomotive boiler, a separating means associated with said inlet connection adapted to separate impurities from the inflowing steam and water, a refill receptacle, means for directing thereto the inflowing steam from the separating means, a boiler, a water line from the refill tank to the boiler, a refill line extending from said boiler to the point of use, a return line from the boiler to the refill tank and a thermostatically operated valve associated therewith and adapted to permit

flow from the boiler to the refill tank when the boiler water reaches a predetermined temperature.

2. In locomotive handling equipment, a blow-off and refill plant which includes an inlet connection adapted to be connected to a locomotive boiler, a separating means associated with said inlet connection adapted to separate impurities from the inflowing steam and water, a refill receptacle, means for directing thereto the inflowing steam from the separating means, a boiler, a water line from the refill tank to the boiler, a refill line extending from said boiler to the point of use, a return line from the boiler to the refill tank and a pressure relief valve associated therewith and adapted to permit flow from the boiler to the refill tank when the boiler pressure reaches a predetermined limit.

20 3. In locomotive handling equipment, a blow-off and refill plant which includes an inlet connection adapted to be connected to a locomotive boiler, a separating means associated with said inlet connection adapted to separate impurities from the inflowing steam and water, a refill receptacle, means for directing thereto the inflowing steam from the separating means, a boiler, a water line from the refill tank to the boiler, a refill line extending from said boiler to the point of use, a return line from the boiler to the refill tank and a pressure relief valve associated therewith and adapted to permit flow from the boiler to the refill tank when the boiler pressure reaches a predetermined limit, a washout tank, a water line extending from the separating means to the washout tank, and a washout line extending from the washout tank to the point of use.

40 4. In locomotive handling equipment, a blow-off and refill plant which includes an inlet connection adapted to be connected to a locomotive boiler, a separating means associated with said inlet connection adapted to separate impurities from the inflowing steam and water, a refill receptacle, means for directing thereto the inflowing steam from the separating means, a boiler, a water line from the refill tank to the boiler a refill line extending from said boiler to the point of use, a return line from the boiler to the refill tank and a pressure relief valve associated therewith and adapted to permit flow from the boiler to the refill tank when the boiler pressure reaches a predetermined limit a washout tank, a water line extending from the separating means to the washout tank and a washout line extending from the washout

tank to the point of use, pumping means in said washout line and means for cooling the water delivered along said washout line.

5. In locomotive handling equipment a blow-off and refill plant which includes an inlet connection adapted to be connected to a locomotive boiler a separating means associated with said inlet connection adapted to separate impurities from the inflowing steam and water, a refill receptacle, means for directing thereto the inflowing steam from the separating means, a boiler, a water line from the refill tank to the boiler, a refill line extending from said boiler to the point of use, a return line from the boiler to the refill tank and a pressure relief valve associated therewith and adapted to permit flow from the boiler to the refill tank when the boiler pressure reaches a predetermined limit, a washout tank, a water line extending from the separating means to the washout tank, and a washout line extending from the washout tank to the point of use, and a cold water line adapted to deliver cold water to the washout line.

6. In a locomotive handling equipment, a blow-off and refill plant which includes an inlet connection adapted to be connected to a locomotive boiler, a refill tank in communication with such inlet connection, a boiler associated therewith, a water line from the refill tank to the boiler, pumping means in said water line, a return line from said boiler to said refill tank and means therein adapted to permit a return flow of water in response to predetermined excess temperatures and pressures in the boiler and a refill line extending from said plant to the point of use.

7. In a locomotive handling equipment a blow-off and refill plant which includes an inlet connection adapted to be connected to a locomotive boiler, a refill tank in communication with such inlet connection, a boiler associated therewith, a water line from the refill tank to the boiler, pumping means in said water line a return line from said boiler to said refill tank and means therein adapted to permit a return flow of water in response to predetermined excess temperatures and pressures in the boiler, burner means for heating said boiler and control means therefor responsive to pressure and temperature conditions in the boiler.

Signed at Chicago, county of Cook and State of Illinois, this 16th day of March, 1927.

MURILLO DOWNER.
